UNITED STATES PATENT OFFICE.

OTTO JAEGER, OF ELKINS PARK, PENNSYLVANIA, ASSIGNOR TO HARRY S. KELSEY,
OF LEXINGTON, MASSACHUSETTS.

DESIGN FOR A FRONT FOR VENDING-MACHINES.

52,481.

Specification for Design.

Patented Sept. 24, 1918.

Application filed June 7, 1918. Serial No. 238,785. Term of patent 14 years.

To all whom it may concern:

Be it known that I, OTTO JAEGER, a citizen of the United States, residing at Elkins Park, in the county of Montgomery and State of Pennsylvania, have invented a new, original, and ornamental Design for a Front for Vending-Machines, of which the following is a specification, reference being had to the accompanying drawing, forming part thereof.

Figure 1 is a perspective view of the front

face of a vending machine. Fig. 2 is a front elevation of the face of the said vending machine. Fig. 3 is a side elevation of fragmentary portion of the front showing the inward slant of the V-shaped portion of the front face.

I claim:

The ornamental design for a front for vending machines substantially as shown.

In testimony whereof I affix my signature.

OTTO JAEGER.
